UNITED STATES PATENT OFFICE.

FRANK E. MILLER, OF NEW YORK, N. Y.

SURGICAL DEVICE.

1,263,456.

Specification of Letters Patent. Patented Apr. 23, 1918.

Application filed December 14, 1917. Serial No. 207,059.

To all whom it may concern:

Be it known that I, FRANK E. MILLER, a citizen of the United States, residing at 17 West 54th street, New York city, N. Y., have 5 invented certain new and useful Improvements in Surgical Devices, of which the following is a clear, full, and exact description.

This invention relates to surgical devices 10 more particularly adapted for truss pads, such for instance as shown in my prior application for patent filed August 22, 1917, Serial No. 187,514. One of the objects of the invention is to provide means for gripping 15 and drawing the epidermis toward an axis which extends outwardly from the body, with a view to producing a new healthy growth at a local part of the body. Another object of the invention is to correlate 20 such means with a truss pad having an apical pressure portion adapted to press toward the rupture, while the gripping and drawing means are adapted to draw the epidermis and peritoneum toward said pressure portion. 25 Other objects of the invention are to provide simple and efficient means for healing a part of the body.

These being among the objects of the present invention, the same consists of certain 30 features of construction and combinations of parts to be hereinafter described and then claimed with reference to the accompanying drawings illustrating one embodiment of the invention in which—

35 Figure 1 is a fragment of a belt, bandage or corset showing one of the improved surgical devices in dotted lines positioned therein;

Fig. 2 is a perspective view showing more 40 clearly the preferred construction of the means for positioning the device;

Fig. 3 is a sectional view of the belt or the like showing one of the improved surgical devices in elevation, the same being positioned for use;

Fig. 4 is a transverse section on the line 4—4, Fig. 5;

Fig. 5 is a longitudinal section on the line 5—5, Fig. 4;

50 Fig. 6 is a reverse plan view of the parts shown in Fig. 5;

Fig. 7 is a detail plan view of the preferred active elements of the device and

55 Fig. 8 is a perspective view of one of the clutches.

Referring to Figs. 1 and 2, a fragment of

a belt, bandage, corset or the like 10, which is adapted to support the improved surgical device, is shown, the same preferably comprising two layers 11, 12, of fabric, the layer 12 being that which is applied directly 60 against the body of the wearer and the layer 11 being the outer layer, said layer 12 being cut out so as to provide a flap 13 for closing a pocket 14, which is disposed between 65 said flap and the outer layer of fabric 11. The side edges of the flap or closure 13 may be stitched or otherwise secured to the edge surrounding the pocket 14 after the surgical device 16 has been placed in the desired position for use. The surgical device 16 is shown in dotted lines in Fig. 1. By reference to my prior application above referred to, it will be seen that the improved surgical device as shown is exemplified in a 70 75 truss pad.

The details of the preferred construction of the improved surgical device are shown in the other figures of the drawings. The device will be specifically described as if 80 relating solely to a truss pad except where otherwise specified. A pad or supporting member 16, comprises two preferably conico-ovate pad or main members 17, 18, each of which is preferably of the same general dimensions. Said members are provided with outer surfaces which are generally conical and these surfaces preferably extend continuously from the apices or apical portions 17^a, 18^a to the margins of said members, 85 thereby or otherwise placing the apices 17^a, 18^a at the highest points of the pad members. Said pad members are placed back to back as shown in Fig. 3 so that the tapering outer surfaces and the apices are presented 90 outwardly away from each other. To hold said members 17, 18 in that position, a socket such as 19, is provided on each member, and these sockets receive a screw stem or spindle 20, which is provided at a point between 95 100 said members with a knob or wrench head 21, whereby said spindle may be rotated to cause said members to approach or recede from each other. A telescoping device 22 holds the said pad or other members in parallelism. It is obvious that the head 21 may be turned by introducing a wrench or tool between the flap 13 and the member 10 before the flap is secured at its edges. Of course, the flap really does not have to be 110 secured at its free edges.

It is preferred that a bicuspid device be

provided, but this is not essential inasmuch as one pad or other member only may be employed. Referring to a single pad or other supporting member, the same is provided with a series of clutch or gripping jaws 23, the relation of which to each other is more clearly shown in Fig. 7, said jaws preferably surrounding and being correlated with a central apical pressure portion 17^a. Said jaws are provided with shanks 24, as shown in Figs. 4, 5 and 8, which are pivoted at 25, to a collar or support 26. The latter is arranged within a pad or other supporting member and may be fixed as shown upon the socket 19 so that it does not move thereon. Said collar or annular support 26, is screw threaded to receive a castellated or other nut 27 serving as a clutch actuating member. Jaws 23 are located just outside of the surface of the pad or other supporting member 17, while the shanks 24, extend through slots 28 in said member, thereby permitting the jaws to be swung or moved to and from the apical member portion 17^a. The inner ends of the shanks 24, are provided with outwardly extending fingers or lugs 29, which are in contact with the clutch actuating member 27, so that by a proper rotation of said member, the jaws 23 may be forced toward the apical pressure portion 17^a. A turning of the clutch actuating member 27, in opposite direction permits the jaws to be swung back.

Assuming that the improved surgical device is in the form of a truss pad, the same will be applied to the pocket 14, so that the apical pressure portion 17^a, will be pointed directly toward the body of the wearer, and if there be another pad member, the apex thereof will point in opposite direction as shown in Fig. 3, and it will constitute an opposing member for the pad-member having said apical portion 17^a. The apical pressure portion 17^a is now engaged with the skin at a point opposite the rupture, and the pressure may be increased by rotating knob or head 21. When the surgical device is first applied to the belt or the like, the apical pressure portion 17^a, and the jaws 23, are caused to engage with the edge of an opening 15, in the flap 13, so as to protrude through said opening. Preferably the surfaces which are to engage the skin are covered with some soft material which will not abrade it. After the device has been placed in position to engage in the opening 15, the edges of the flap are sewed or otherwise attached to the belt or the like, but this is not done until after the desired adjustment of the parts has been obtained.

The function of the movable clutching or gripping jaws 23, will now be described. Assuming that the apical pressure member has been engaged over the rupture, the part 30 of the abdomen will be deflected into

substantially the shape shown by the dot and dash line 30, Fig. 4. There will be an extreme depression at 31, caused by the extremity of the apical pressure portion. The rotary member 27, is now turned in proper direction, by introducing a suitable tool through a hole in the fabric covering, or the flap or closure may be left unsecured for the introduction of such a tool, to cause the jaws 23, to be moved toward the axis of the apical pressure portion which will result in drawing the epidermis and peritoneum into about the shape indicated at 32, by the broken line. It will be seen that a portion of the dermis will be gathered or clutched between the jaws 23, and the apical pressure member, so that intact parts of the dermis and peritoneum are moved over the rupture. The parts are held in that position by the wearer of the truss, after the parts of the truss have been properly adjusted and fixed, for a period of say, a day. The truss is then taken off at night and the action repeated daily for a sufficient length of time until there will result the location or growth of new dermis over the ruptured part, thereby affording a much greater resistance to the protrusion of the intestines. The additional advantage gained by the repeated application of the device is that the parts are massaged by it and there is a new distribution of the muscles, thereby tending eventually to produce a healthy body and cure the rupture.

It will be seen that the improved device 100 is capable of an entirely different application in surgery inasmuch as when the device is not in the form of a truss pad, the apical pressure member will of course, be omitted, in which case the jaws 23, may be used for 105 the purpose of massaging a local point of the body by repeated rotations and reverse rotations of clutch actuating member 27; and it will furthermore be seen that the dermis may be gathered up and drawn around an 110 axis which extends outwardly from the body, as for instance around a wound, carbuncle, etc. If the surgical device is made as a bicuspis truss pad, it is obvious that one of the cusps only need be provided with the 115 skin clutching and drawing jaws, the other being left plain as shown in Fig. 3. This adapts the device for reversal if that be desired. When reversed the other pad member 18, acts only as a pressure member.

It is obvious that the invention is capable of modification, without departing from the spirit and scope thereof as expressed in the claims.

What I claim as new is:

1. In a surgical device, the combination of 125 a main member having an apical pressure-portion, said member being provided with apertures and skin gripping means correlated with said member, and operable 130

through said apertures relatively to said apical portion without affecting it.

2. In a surgical device, the combination of a main member having an apical pressure-portion, said member being provided with apertures and skin gripping means correlated with said member, and operable through said apertures relatively to said apical portion without affecting it, said gripping means comprising clutch-members surrounding said apical portion.

3. In a surgical device, the combination of an adjustable main pressure member having an apical pressure portion, and provided with apertures around said apical portion, and skin gripping means correlated with said apical portion, and means for operating said clutch-members through said apertures toward said apical portion without adjusting said pressure member.

4. In a surgical device, the combination of a main pressure member having an apical pressure-portion, and provided with apertures around said apical portion, and a series of swingable clutch-members surrounding said apical portion and operably disconnected therefrom, said clutch members protruding through said apertures.

5. A surgical device comprising an apertured truss pad provided with means protruding through the apertures of said truss pad for gripping the epidermis.

6. A surgical device, comprising, in combination, a truss pad having an apical pressure portion, movable gripping means on said pad surrounding the axis of said pressure portion which is arranged to extend perpendicularly to the surface of the body of the wearer of the device, said gripping means being arranged within the outer margin of said pad, and means for simultaneously actuating said gripping means to cause the same to grip and draw the epidermis toward said pressure portion.

7. In a surgical device, the combination of a main pad-member provided with apertures, an opposing member at the outer side of said main pad member, the latter being adjustable thereon toward the wearer, and having an apical pressure-portion and means correlated with said apical portion and protruding through said apertures for drawing the dermis and peritoneum toward said apical portion.

8. In a surgical device, the combination of a main pad-member provided with apertures, an opposing member at the outer side of said main pad member, the latter being adjustable thereon toward the wearer, and

having an apical pressure-portion, and means correlated with said apical portion and protruding through said apertures and independently operable for drawing the dermis and peritoneum toward said apical portion.

65

9. In a surgical device, the combination of a main pad-member, having an apical pressure-portion, and apertures surrounding said apical portion, an opposing member at the outer side of said main pad-member, means for adjusting said main pad-member away from said opposing member, means correlated with said apical portion and protruding through said apertures for drawing the dermis and peritoneum toward said apical portion, and means for adjusting said drawing means independently of the adjustment afforded by said pad adjusting means.

70

10. In a surgical device, the combination of two separate, back opposed, pad members, provided with conical outer surfaces, the apices of which are located on an axis transverse of said members, means for adjusting said members to vary their distance apart, and means for drawing the dermis and peritoneum toward said axis.

75

11. In a surgical device, the combination with supporting means, such as a belt provided with a pocket, of a reversible pad of firm material comprising two substantial similar pressure pad members, arranged symmetrically, back to back and held in the desired position in said pocket by tension, one of said members being provided with means for drawing the dermis and peritoneum toward an axis which extends through a rupture.

80

12. In a surgical device, the combination of two separate elongated pad members having oppositely presented high points located on an axis offset from the midlengths of said members, and the outer surfaces of said members being on a slope from said high points to the margins of said members, and in all other respects said members having substantially the same shape and dimensions so that they are substantially identical, means for adjustably connecting said members, means for holding said members in relatively fixed position laterally, to provide a symmetrical truss pad, and means for drawing the dermis and peritoneum toward said axis.

85
